CLAIM

The ornamental design for a kaleidoscope, as shown and described.

DESCRIPTION

FIG. 1 is a perspective view of a kaleidoscope showing my new design;

FIG. 2 is a front elevational view thereof;

FIG. 3 is a side elevational view thereof;

FIG. 4 is a top plan view thereof;

FIG. 5 is a bottom plan view;

FIG. 6 is a cross-sectional view taken substantially in the plane indicated by lines 6—6 of FIG. 2;

FIG. 7 is a perspective view of a modified embodiment of the design shown in FIGS. 1-6;

FIG. 8 is an elevational view thereof;

FIG. 9 is a top plan view;

FIG. 10 is a bottom plan view; and

FIG. 11 is a cross-sectional view thereof corresponding to section line 6—6 of FIG. 2.
